S. NICHOLS

STOOL

Filed Dec. 18, 1922

INVENTOR.

STEPHEN NICHOLS

BY

AT TORNEY

UNITED STATES PATENT OFFICE.

STEPHEN NICHOLS, OF DENVER, COLORADO.

STOOL.

Application filed December 18, 1922. Serial No. 607,845.

To all whom it may concern:

Be it known that I, STEPHEN NICHOLS, a citizen of the United States, residing at Denver, in the county of Denver and State of Colorado, have invented certain new and useful Improvements in Stools, of which the following is a specification.

My invention relates to stools for use of motormen, engineers and conductors of rail-way cars, and its principal object is to provide in combination with a stationary support, a resiliently mounted seat which is adjustable to accommodate persons of different statures and to vary its distance from the controller or other apparatus operated by its occupant.

Other objects of the invention reside in details of construction all of which will be fully disclosed in the course of the following description made with reference to the accompanying drawings.

In the drawings in the several views of which corresponding parts are similarly designated,

25 Figure 1 represents a side elevation of my improved stool;

Figure 2, a section taken on the line 2—2, Figure 1, looking upwardly in the direction of the arrows drawn across said line;

30 Figure 3, a vertical section along a plane indicated by the line 3—3, in Figure 2;

Figure 4, a fragmentary section on the line 4—4, Figure 2;

Figure 5, a section along the line 5—5, 35 Figure 1, drawn to an enlarged scale; and

Figures 6 and 7, similarly enlarged sections taken respectively on the lines 6—6 and 7—7, Figure 1.

Referring more specifically to the drawings, the reference character 2 designates a pedestal composed of a tubular standard 3 which is fastened in an upright position upon a flanged foot 4.

The standard is preferably fastened upon the foot by welding the one in an opening of the other and the foot has in its flange a number of holes for the passage of bolts 5 by means of which it is fastened to the floor of the car upon which the pedestal is 50 supported.

Slidably fitted in telescoping relation to the standard, is a tube 6 which at its upper end carries an internally screw-threaded ferrule-shaped head 7 to support the correspondingly threaded stem 8 of the seat of the stool.

The tubular extension 6 of the hollow standard rests upon a coiled spring 9 placed within the latter and it is held against rotation by means of a cap-screw 10 which passes through a longitudinal slot 12 of the member of the stationary support.

The before mentioned stem 8 has in rigid connection with its upper extremity, a transversely extending rectangular slide plate 13 which on its underside is provided with series of indentations 14 that extend along its parallel longitudinal edges to receive the end of a set screw by which the seat of the stool is held in its adjusted positions.

The seat consists of a slightly concaved wooden block 15 provided at its underside with two parallel longitudinally grooved guide members 16 which co-operate with the slide 13 to support the seat upon the standard through the intermediary of the threaded stem 8, the tubular extension 6 and the spring 9.

The members 16 are fastened to the seat by screws 17 and they have in a central enlargement 18 of their lower portions, screw-threaded openings to receive the set-screw 19 which by entering the indentations of the slide plate secures the seat in any of a plurality of predetermined positions.

In the construction shown in the drawing but one set-screw is used at one side of the seat for the above described purpose, but it will be apparent that two screws may be used at opposite sides of the seat if so desired or that in case the screw-thread of the hole through which the screw passes, should become worn by long and constant use, the screw can be transferred to the hole at the other side of the seat and there perform the same function of holding the seat against displacement on the slide plate of the stem 8.

It is desirable to slightly upset the end of the set-screw as indicated at 20 in Figure 3, 10 and thereby prevent of its being accidentally detached from the guide member with which it is associated.

Having thus described my improved stool, I desire it understood that variations in the 105 construction and co-operative arrangement of the parts thereof may be resorted to within the scope of my invention as defined in the hereunto appended claim.

The stool as shown and described, provides a comfortable seat which by reason of its resilient support, saves its occupant from

the unpleasant and frequently harmful effects of the vibrations and shocks of the vehicle to which the stool is attached; the vertical adjustability of its screw-threaded stem 5 in the moving member of the standard permits of elevating or lowering the seat according to the stature of its occupant and the transverse adjustment of the seat on the stem allows of its being moved with relation 10 to the controller box or other apparatus to place it within convenient and easy reach of the person who occupies the seat.

What I claim and desire to secure by Letters Patent is:

15 A stool of the character described, comprising a seat, spaced parallel guide members secured to the under side of the seat and provided at their inner opposed edges with

longitudinal guide grooves, a rectangular slide plate having its side edges fitted in the said grooves and provided between the guide members with a depending socket, said slide plate being provided in its lower face adjacent each side edge with depressions arranged at intervals and housed within and protected by the grooves of the guide members, a set screw mounted in the guide members and arranged to engage the said depressions for securing the slide plate and seat in relative adjustment and a pedestal having its upper end fitted in the socket of the slide plate.

In testimony whereof I have affixed my signature.

STEPHEN NICHOLS.
